Julius A. Schwantes, Maplewood, N. J.; Laura Schwantes, executrix of Julius A. Schwantes, deceased, assignor to Colgate-Palmolive-Peet Company, Jersey City, N. J., a corporation of Delaware

Application January 31, 1936, Serial No. 61,645

6 Claims. (Cl. 229—16)

This invention relates to packages, and more particularly to an improved merchandising package which is simple in construction, inexpensive to manufacture, neat and attractive in appearance, which fully protects the contents during shipment and handling, and which may be assembled and packed rapidly and economically, substantially entirely by automatic machinery.

According to the present invention, the improved merchandising package comprises a shell or container assembled from a single blank of paperboard material, and which, when assembled, is rigid and strong and fully supports and protects the article packed therein. The assembled shell has substantially smooth, interior wall surfaces which permit the rapid insertion of the article therein without obstruction, interference or damage to the article during insertion. Prior to inserting the article into the shell, it is preferably enclosed in a suitable wrapper, so made as to neatly surround the article and cushion the same against the damaging effects of jolts and jars when contained within the shell. The shell, made in accordance with this invention, is susceptible of being formed into various distinctive prismatic shapes, other than the customary parallel-opiped shape used in packaging. The completed package thus possesses a striking appearance, and an attractive sales appeal. The shell, when packed and sealed, may, if desired, be enclosed within an attractive wrapper which is folded in such a manner as to neatly surround the shell, and at the same time permit application thereof by automatic machinery.

The shell is adapted to be formed from a single blank of paperboard material which may be cut and scored by means of automatic machinery, with very little waste of material, and may be assembled with a minimum of gluing operations. Means are provided to permit quick and ready access to the contents when the same are to be removed for use, but which is so sealed as to prevent the contents from being removed and replaced, or otherwise tampered with, without leaving visible evidence that such tampering has taken place.

The merchandising package which is the subject matter of this invention is especially adapted to the packaging of soap cakes and similar articles which possess oval or other irregular shapes which make them otherwise difficult to package.

In the drawings accompanying and forming part of this specification, certain specific disclosure of the invention is made for purposes of explanation, but it will be understood that the

details may be modified in various respects without departure from the broad aspect of the invention. In the drawings:

Fig. 1 illustrates a blank which has been suitably cut and scored and ready to be formed into a shell or container;

Fig. 2 is a perspective view of the inner wrapper about to be applied to the article packaged;

Fig. 3 is a perspective view of the assembled shell with the wrapped article in position to be inserted therein;

Fig. 4 is a perspective view of the shell as it appears when partially packed and partially closed;

Fig. 5 is a perspective view of the outer wrapper about to be applied to the closed shell;

Fig. 6 is a perspective view of the completed, fully assembled package;

Fig. 7 is a perspective view illustrating the manner in which the package may be opened to obtain access to the contents; and

Fig. 8 is a fragmentary view showing a portion of a modified form of blank.

According to the present invention the article 1, either of regular or irregular shape, is preferably enveloped in an inner wrapper 2, the wrapped article then inserted into a relatively rigid shell 3 and the shell sealed and wrapped in a relatively flexible outer wrapper 4 to constitute the complete merchandising package 5.

Referring more particularly to Fig. 1, a blank 10 of paperboard material is cut and scored suitably for forming a shell preferably having sufficient strength and rigidity to maintain a predetermined shape. The blank 10 may comprise a side wall or front section 11, a bottom section 12, a side wall or back section 13 and a top section 14. The front section 11 preferably is rectangular, and has laterally extending end wall flaps 15. Each flap 15 may be integrally attached to the front section 11 by a narrow section or "bevel" section 16 defined by longitudinal hinge or score lines 17 and 18, or other portion of increased flexibility. Although reference is made to score lines, the desired increased flexibility may be provided in other ways without departing from the scope of the invention.

Extending from the end of each flap is a tuck-in tab 19 bendable about a score line 20, and preferably of slightly less width than the bevel section 16 so that the edge 21 is in alignment with the bevel. The edge 21 has an inwardly curved portion 22, and the tab 19 at its point of attachment to the flap 15 is substantially equal to the width of the flap.

Extending from the free end of the front section 11 is a tongue 25 having inclined side edges 26. The tongue 25 is bendable about a score line 27 extending along its base, and the base preferably is slightly narrower than the front section 11, thus providing free edges 28. Spaced parallel lines of perforations may be provided in the tongue 25 extending perpendicularly to the score line 27, and crossing the same, and a semicircular score line 30 may be provided in the front section 11 in continuation of the lines 29 and defining therewith a break-out portion 31.

The bottom section 12, which may be generally rectangular, may be integrally attached to the front section 11 and bendable about a score line 35, and may be slightly wider than the front section 11, with the side edges in alignment with the central portions of the bevel section 17. The bottom section 12 preferably is attached to the front section 11 over a distance substantially equal to the width of the front section 11. Triangular fold-in tabs 37 extend laterally from the bottom section 12, and are bendable about score lines 40, each tab 37 having a front edge 38 perpendicular to the score line 40, and a rear edge 39 inclined to the line 40. Each tab 37, preferably, is attached to the bottom section 12 over less than the width of the corresponding edge of the bottom section 12, and the corners 36 and 42 of the bottom section 12 are rounded.

Integrally attached to the bottom 12 along a score line 41, is a rectangular back section 13 similar to the front section 11. Laterally extending from the back section 13 are end wall flaps 45, each of which preferably is attached by a longitudinal bevel section 47 defined by score lines 48 and 49. The flaps 45 are generally rectangular and each has an inclined lower edge 46 extending to the score line 48. Each flap 45 terminates short of the end of the back section 13, and the upper edge 50 of each bevel section 47 is inclined.

Integrally secured to the free end of the back section 13 is a top section 14 bendable about a score line 55, and having a generally rectangular shape similar to that of the bottom section 12, the corners 56 and 57 being rounded similarly to those of the bottom.

The blank may be set up to form a shell of self-sustaining form by bending up the flaps 45 along score lines 49, and the tabs 37 along lines 40, and bending the back section 13 along the score line 41 and the front section 11 along the score line 35. The flaps 15 are then bent up along lines 18, and secured to the flaps 45 and tabs 37, preferably by pasting or gluing. It will be noted that each tab 37 is complementary to the corresponding flap 45 and the edges 39 lie adjacent the edges 46, whereby each flap 45 and corresponding tab 37, together with the flap 15, constitute a generally rectangular wall of double thickness and having a substantially smooth interior face. The edges 39 and 46 may abut over at least a portion of their length and thus reinforce the container adjacent the bottom. The four walls standing from the bottom of the container may be designated generally as side walls, and the several sections of the blank which form these walls may be designated as side wall sections.

The front section 11, the rear section 13, and the tabs 37 are connected to the corresponding edge portions of the bottom section over less than the length thereof to leave exposed corner edges 38 and 42. Preferably the corners 36 and 42 are rounded and, when the container is set up, are

adapted to abut the adjacent bevel sections 16 and 47 to provide a support for the forming of the bevel sections 16 and 47 into rounded edges. The score lines 17, 18, and 48, 49 permit the bevel sections 16 and 47 to conform to the shape of the corners 36 and 42.

Where the corners 36 and 42 are rounded, as shown in Fig. 1, the bevel sections will be formed into generally rounded edges. However, if desired, other shapes may be given to the corners of the bottom section to cause the bevel sections to assume other than rounded shapes. For example, in Fig. 8 is shown a blank 110, which may be generally similar to the blank 10, except that the corners 136 and 142 of the bottom section 112 are cut off angularly. The blank 110 may be set up in a manner similar to that above described, to form a container (not shown), and the bevel sections 116 and 147 abut the edges of the corners 136 and 142, and are given the shape of a flat angular bevel. It will thus be apparent that various attractive shapes may be given to a container by varying the relative sizes and shapes of the end-wall sections and cooperating side-wall sections. By providing a container wherein the edges take the form of rounded or flat bevels, it is possible to form a shell having a more attractive or otherwise more desirable shape than if the edges are formed without bevels.

One or more of the operations of setting up the blank and inserting the article to be packaged may be carried out simultaneously, and these operations may be carried out either manually or partially or substantially entirely by the use of suitable automatic machines (not shown).

For the purpose of illustration, a package is shown containing a flat, solid article of oval cross-section, as for example a soap cake or tablet. The wrapper 2 may be a sheet of air- and moisture-proof material such as waxed paper, transparent cellulosic material, or other suitable material; the material generally will be dependent upon the nature of the article. In some cases, however, it may be desirable to insert the article in the shell without providing any inner wrapper.

The article 1, either with or without an inner wrapper, may be inserted in the open end of the partially assembled shell or container 3, as illustrated in Fig. 3. Thereafter the tabs 19 are bent down to overlie the end of the shell, and the tongue 25 bent down to overlie the tabs 19. The shell 3 is closed and sealed by bending down the top section 14 and securing it to the tongue 25, preferably by an adhesive such as paste, glue or other material, to form a closed top wall opposite the bottom wall, both of which walls may be designated as end walls.

Adhesive may be applied either to the tongue 25 or to the top section 14. Where adhesive is applied by machinery to the top 14 over a zone extending across the entire width thereof, the tongue 25 may hold the top sufficiently out of engagement with the tabs 19 so that the latter will not be substantially secured to the top section 14, as will appear hereinafter; this ensures easy opening of the shell. However, when the shell is sealed, the same cannot be opened without leaving evidence of having been tampered with, thereby preventing removal and substitution of the contents.

The shell 3 may then be wrapped in an outer flexible wrapper 4 which may be sheet material such as paper, transparent cellulosic sheet material either single thickness or laminated, or other flexible material which may be suitably printed,

engraved, embossed or otherwise decorated, if desired, to present an attractive appearance. The outer wrapper 4 may be applied in the usual manner of wrapping packages by overlapping and 5 folding the same to form overlapping flaps 60 and 61, which may be secured together, preferably by an adhesive.

The package may be opened by removing the outer wrapper 4, or a portion thereof, and severing the shell along the perforated line 30, by 10 means of the fingernail of the user, or by exerting pressure on the break-out portion 31, whereafter the top section 14 may be raised to cause the tongue 25 to be torn along the lines 70, thus 15 permitting the separation of the top from the tongue. A portion 11 of the tongue adheres to the top section 14, and the attached break-out portion 31 constitutes a tab or handle for assisting in raising the top. The tabs 19 do not 20 adhere to the top section 14 sufficiently to resist appreciably the opening movement of the top section 14.

The provision of a container or shell which is of such construction and rigidity that it will retain a predetermined shape, will permit the commodity when enclosed in the shell to be easily and neatly enclosed in a wrapper or envelope of relatively flexible material. Thus the commodity, even though of irregular shape, may be wrapped 25 in an attractive wrapper, such as a previously decorated sheet of paper or other wrapper, without any unsightly wrinkles or folds.

The use of a shell having beveled or rounded edges, provides a package of neat appearance, and 30 permits the same to be wrapped readily in a tightly applied wrapper without liability of tearing or cracking the wrapper. The provision of double lines of flexibility also provides a greatly increased flexibility of the blank from which the 35 shell is formed, with a lesser liability of undue weakening of the blank than where a shell bent along a single line of flexibility and having square edges is employed.

The novel manner in which the side walls are 40 constituted ensures smooth interior faces from the walls and eliminates any possibility of the article or the inner wrapper being damaged during insertion into the shell, and prevents obstruction to the entry of the article even though 45 it may be substantially as large as the inside dimension of the container. The provision of the complementary portions for forming a side wall in the manner employed in the present invention also provides a certain amount of reinforcing of the adjacent portions of the container.

While certain novel features of the invention have been disclosed and are pointed out in the annexed claims, it will be understood that various 50 omissions, substitutions and changes may be made by those skilled in the art without departing from the spirit of the invention.

What is claimed is:

1. A container-forming blank of paperboard material including, a bottom section, side wall sections hinged to said bottom section along opposite sides thereof, generally triangular shaped tabs hinged to said bottom section along opposite ends thereof, said bottom section having a free beveled corner intermediate each tab and side wall section, and a pair of end wall flaps carried by each of said side wall sections and hinged to corner formations, one pair of said end wall flaps having a beveled edge at 65 one end of each flap adapted to abut the adjacent edge of the adjacent triangular tab when the container is assembled, each of said corner formations comprising a relatively narrow panel bounded by two hinge lines connecting the panel to the adjacent end wall flap and the adjacent side wall section, each of said corner panels having a width corresponding to the adjacent beveled corner of said bottom section. 5
2. A paperboard blank for forming a container including, a bottom section, side wall sections hinged to said bottom section along opposite sides thereof, tabs hinged to said bottom section along opposite ends thereof, said bottom section having a free beveled corner intermediate each tab and side wall section, a pair of end wall flaps carried by each of said side wall sections and hinged to corner formations, each of said corner formations comprising a relatively narrow panel bounded by hinge lines connecting the same to the adjacent end wall flap 10 and the adjacent side wall section, each of said corner panels having a width and contour substantially corresponding to the adjacent beveled corner of said bottom section, a tuck-in tab extending from one end of each of two end wall flaps, each of said tuck-in tabs having a free beveled corner generally similar in shape and contour to the corresponding beveled corner of said bottom section, and a cover section hinged to one of said side wall sections. 15
3. A container formed from a single blank of paperboard material including, a bottom section, side wall sections hinged to said bottom section along opposite sides thereof, generally triangular shaped fold-in tabs hinged to said bottom section along opposite ends thereof, said bottom section having a free beveled corner intermediate each tab and side wall section, a pair of end wall flaps carried by each of said side wall sections and hinged to corner formations, one pair of said end wall flaps having a beveled edge at one end of each flap adapted to abut the adjacent edge of the adjacent triangular tab, each of said corner formations comprising a relatively narrow panel bounded by hinge lines connecting the panel to the adjacent end wall flap and the adjacent side wall section, each of said corner panels having a width and contour generally corresponding to the adjacent beveled corner of said bottom section. 20
4. A package for an article of merchandise including, a relatively rigid container body and a wrapper enclosing said body, said container body including, a bottom section, side wall sections hinged to said bottom section along opposite sides thereof, fold-in tabs hinged to said bottom section along opposite ends thereof, said bottom section having a free beveled corner intermediate each tab and side wall section, a pair of end wall flaps carried by each of said side wall sections and hinged to corner formations, each of said corner formations comprising a relatively narrow panel bounded by hinge lines connecting the same to the adjacent end wall flap and the adjacent side wall section, each of said corner panels having a width and contour generally corresponding to the adjacent beveled corner of said bottom section, adjacent end wall flaps being secured together in overlapping relationship to provide end walls, an inwardly projecting tuck-in tab hinged to the cover end of each of two end wall flaps, and a cover section hinged to one of said side wall sections generally corresponding in shape and size to said bottom section, each of said tuck-in tabs. 25

- 5 having a free beveled corner generally similar in shape and contour to the corresponding beveled corner of said bottom section, said body enclosing wrapper closely conforming to the side and end wall sections and intermediate beveled corner formations of said container body, the end portions of said wrapper being folded in overlapping relationship across the bottom and cover sections of the container body.
- 10 5. A container-forming blank of paperboard material including, a bottom section, side wall sections hinged to said bottom section along opposite sides thereof, fold-in tabs hinged to said bottom section along opposite ends thereof, said bottom section having a free beveled corner intermediate each tab and side wall section, and a pair of end wall flaps carried by each of said side wall sections and hingedly connected thereto by corner formations, each of said corner formations comprising a relatively narrow panel bounded by hinge lines connecting the same to the adjacent end wall flap and to the adjacent 15 side wall section, each of said corner panels having a width and contour generally corresponding to the adjacent beveled corner of said bottom section, an inwardly projecting tuck-in tab hinged to the cover end of each of two end wall flaps, and a cover section hinged to one of said side wall sections for closing the container, each of said tuck-in tabs having a free beveled corner generally similar in shape and contour to the corresponding beveled corner of said bottom 20 section adapted to abut the interior surface of the adjacent corner formation.
- 15 25

lar in shape and contour to the corresponding beveled corner of said bottom section.

6. A container formed from a single blank of paperboard material including, a bottom section, side wall sections hinged to said bottom section along opposite sides thereof, fold-in tabs hinged to said bottom section along opposite ends thereof, said bottom section having a free beveled corner intermediate each tab and side wall section, a pair of end wall flaps carried by each of 10 said side wall sections hingedly connected thereto by corner formations, each of said corner formations comprising a relatively narrow panel bounded by hinge lines connecting the same to the adjacent end wall flap and to the adjacent 15 side wall section, each of said corner panels having a width and contour generally corresponding to the adjacent beveled corner of said bottom section, an inwardly projecting tuck-in tab hinged to the cover end of each of two end wall 20 flaps, and a cover section hinged to one of said side wall sections for closing the container, each of said tuck-in tabs having a free beveled corner generally similar in shape and contour to the corresponding beveled corner of said bottom 25 section adapted to abut the interior surface of the adjacent corner formation.

JULIUS A. SCHWANTES.
